FLASK TURNOVER FOR FOUNDRY
MOLDING MACHINES

Stanley James Gedris, Grand Rapids, Mich.

Application July 28, 1950, Serial No. 176,507

5 Claims. (CL. 214—115)

1

This invention relates to hoists and more particularly to an elevator or hoist particularly designed to automatically grasp and release a foundry mold having an outwardly extending flange, or its mechanical equivalent. My invention relates to the article clasping portion of the hoist rather than to the means by which the hoist is elevated or lowered.

This application is a continuation-in-part of my copending application entitled "Molding Machine," Serial No. 723,025, filed January 20, 1947, now abandoned.

Although my novel hoist is adapted to uses other than in the foundry field, I shall describe my hoist as it is related to the foundry field because it is particularly adapted to solving difficulties experienced in that field with flask handling equipment. In the handling of foundry flasks, particularly after the mold has been formed in them, it is necessary that the flask be handled without excessive jarring or shocks. Therefore, any automatic mechanism designed to grasp and release the flask must be capable of seating and unseating the flask from its stationary position without sudden acceleration. This requires a positive and precise mechanism.

Because of the weight of foundry flasks, the hoist must be adapted to handling heavy loads. At the same time, because of the conditions attendant conventional foundry operations, the mechanism must be simple and not require precise or wear-sensitive parts. Foundry operations involve the use of quantities of abrasive and corrosive materials creating serious maintenance problems wherever precision machinery is involved. Thus, it is essential to eliminate precise and close tolerance operating parts whenever possible.

It is, therefore, a primary object of my invention to provide a hoist mechanism adapted to grasping and releasing articles without jarring the articles.

It is a further object of my invention to provide such a hoist, the construction of which involves no precision or close tolerance parts.

It is an additional object of my invention to provide such a hoist which is adapted to positive operation even when handling heavy loads.

These and other objects and advantages of my invention will be seen immediately by those acquainted with the materials handling art, particularly that phase of it involving foundry equipment, upon reading the following specification and drawings.

In the drawings:

2

Figure 1 is a side elevation view of my improved flask hoist showing a portion of the flask conveyor cooperating with the hoist.

Figure 2 is a sectional end elevation view of my improved flask hoist taken along the plane II—II of Figure 1 and showing the hoist intermediate the ends of its downward travel.

Figure 3 is a sectional side end elevation view of my improved flask hoist taken along the same plane as Figure 2 but showing the hoist intermediate the ends of its upward travel.

Figure 4 is a sectional view of my improved flask hoist taken along the plane IV—IV of Figure 1 but not showing the tracks guiding the hoist.

Figure 5 is an enlarged, fragmentary side elevation view of one of the guide tracks for my improved flask hoist showing the operation of the switch track.

20 In executing the objects and purposes of my invention I have provided a hoist having a head from which depends a pair of opposed, pivoted, clamping arms, resiliently urged away from each other. These arms are held at a suitable minimum spacing by engagement with a track of a dog or guide roller on each of the arms. The track provides a release for the arms after an article clasped by the arms has been deposited. The track then forces the arms together again to clasp the next article.

In the following description the terms "upwardly" and "downwardly" are frequently used and are to be taken as meaning "upwardly" as shown in Figure 1 and "downwardly" away therefrom. The terms "inwardly" and "outwardly" are also freely used and are to be taken as "inwardly" toward the geometric center of the hoist and "outwardly" away therefrom.

Referring to the drawings in greater detail the numeral 1 indicates a frame having uprights 2, upper cross beams 3, intermediate cross beams 4, lower cross beams 5, and base beams 6. Supported on the upper cross beams 3 is a top beam 7 from which depends a double acting cylinder 8 having a piston 9. Mounted on the lower end of the piston 9 is a shaft 10 having a horizontal cross bar 11 on each of its ends. The shaft 10 together with the cross bars 11 constitute the head of the clasping assembly.

45 A pair of somewhat vertical arms 20, joined adjacent their lower ends by a brace 21, are each pivotally mounted adjacent their upper ends to one end of the cross bars 11. A pair of arms 20a similar to the arms 20 and having a brace 21a 50 are mounted adjacent their upper ends to the

other of the ends of the cross bars 11. Each of the arms 20 and 20a have an upwardly extending portion above the cross bars 11. The upwardly extending portions of the arms 20 and 20a are joined by a pair of springs 22, each spring extending between one arm 20 and one arm 20a. The arms 20 and 20a are each, at their lower ends, provided with a somewhat horizontal flange 23 and 23a, respectively. The flanges 23 and 23a are directed toward each other. The head, arms 20 and 20a, springs 22, braces 21 and 21a and horizontal flanges 23 and 23a together constitute the clasp assembly or element.

A pair of guide rollers 24 (Figs. 2 and 3) are mounted on each of the braces 21 and 21a by means of outwardly extending mounts 25. Each of the guide rollers 24 cooperates with one of the four guide tracks 30. Since each of the guide tracks 30 is identical, for the sake of brevity, I shall describe them as though there were only one.

The guide track 30 includes a primary track member 31 having an upper, inward, vertical portion 32 and a lower, outwardly offset portion 33 connected by an inclined portion 34. The primary track member 31 is mounted on a standard 35 supported by the cross beams 4 and 5. Inwardly of the offset portion 33 and aligned with the vertical portion 32 is a secondary track member or switch track 36 (Fig. 5) pivotally mounted by the pin 37 at its lower end to the standard 35. The offset portion 33 extends substantially below the lower end of the switch track 36. This extension is at least equal to the diameter of the roller 24. Substantially above the pin 37, a peg 38, mounted on the switch track 36, extends through a slot 39 in the standard 35. A spring 40, coiled about the pin 37 and having one end bearing against the under surface of the cross beam 5 and its other end bearing against the peg 38, urges the peg outwardly and the switch track 36 into alignment with the vertical portion 32 of the primary track member 31. The outward end of the slot 39 acts as a stop when the switch track 36 is aligned with the vertical portion 32 of the primary track 31. By reason of the slot 39, however, the switch track 36 is enabled to pivot inwardly about the pin 37 when subjected to sufficient urging to overcome the force of the spring 40.

I have described one of the four identical guide tracks 30. The guide tracks are arranged in pairs, one pair on each side of the hoist element. The guide tracks making up each pair are spaced apart a substantial portion of the width of the hoist element. One of the rollers 24 cooperates with each of the guide tracks 30.

My improved flask hoist is designed to be used in connection with the molding machine described in my copending application entitled "Automatic Foundry Molding Machine" and with the flask conveyor described in my copending application entitled "Flask Conveyor for Foundry Molding Machine." To clarify the operation of my improved flask hoist, I have illustrated, in Figure 1, a fragmentary portion of the flask conveyor of my automatic molding machine.

Horizontally aligned with the lower cross beams 5 are a pair of rails 50 forming a conveyor track 51. The rails 50 extend between the uprights 2 and their ends are supported on a beam 58 (Fig. 4) extending between two of the uprights 2. Along the conveyor track 51 but adjacent the flask hoist is a mold making station 52. A carriage 53 is, by means of the wheels 62, mounted on

the outer rails 59 for reciprocating travel into and out of the mold making station 52. The carriage 53 is actuated by means of the double acting cylinder 54. By means of the gripping dogs 55 and the pusher dogs 56, the flasks 57 are individually moved, step by step, first into the mold making station and then into the flask hoist. The clasp element, in its raised position, is so disposed that the flasks 57, as they are pushed off the ends of the rails 50, will be supported by the engagement of the horizontal flanges 23 and 23a with the upper rim 60 of the flasks. More detailed description of the mold making station and the flask conveyor is unnecessary since they are fully illustrated and described in my above identified copending application and constitute but one of several ways the flask could be placed in my flask hoist.

Operation

The flasks 57 enter the flask hoist while it is in raised position (Fig. 1). In this position of the hoist the arms 20 and 20a are in their inward position. The flanges 23 and 23a seat under the rim 60 of the flask and are maintained in this position by the contact between the rollers 24 with the vertical portion 32 of the primary track 31. The hoist is then lowered by downward actuation of the cylinder 8, lowering the flask 57 with it. The roller 24 will pass from the vertical portion 32 of the primary track to the switch track 36, which, being aligned with the vertical portion 32, will continue to maintain the arms 20 and 20a in their closed or inward position.

Before the rollers 24 reach the lower ends of the switch tracks 36, the flask 57 will come to rest upon a suitable support such as a mating flask 61. The clasp element will continue to move downward for a short distance after the flask 57 has come to rest, thus, disengaging the flanges 23 and 23a from the rim 60. When the rollers 24 reach the lower ends of the switch tracks 36, under the urging of the springs 22, the arms 20 and 20a will move outwardly until stopped by contact with the offset portion 33 of the primary track 31. At the same time the direction of movement of the clasp element is reversed. As the clasp element moves upwardly, contact between the inclined portions 34 of the track and the rollers 24 will again force the arms 20 and 20a inwardly or toward each other. Under the urging of the rollers 24, the switch tracks 36 will pivot inwardly to permit the rollers to pass from the inclined portions 34 to the vertical portions 32 of the primary tracks 31. As soon as the rollers 24 have passed, the switch tracks 36 will again move back into alignment with the vertical portions 32 of the primary tracks.

The clasp element will stop its upward movement with the horizontal flanges 23 and 23a positioned to receive the next flask from the molding station 52. The limits of vertical travel of the clasp element are determined by the maximum stroke of the piston 9. The piston 9 may be operated hydraulically or pneumatically, or suitable electrically operated equipment may be substituted for the cylinder 8 and piston 9. A suitable arrangement of conventional controls may be employed to time the operation of my hoist. The controls may be employed to time the operation of my hoist. The controls may be made to coordinate the operation of my hoist with the operation of the conveyor moving the flasks into the hoist and the mechanism to be employed for removing the flasks from the hoist.

Such a coordinated system is described in my co-pending application entitled "Automatic Foundry Molding Machine," Serial No. 176,510, filed July 28, 1950.

Numerous modifications of my invention may be made, each without departing from the principle of my invention. Each of such modifications is to be considered as included in the hereinafter appended claims unless these claims by their language expressly provide otherwise.

I claim:

1. In a hoist for a foundry flask, the combination comprising: a frame; a clasp member including a vertically reciprocable head and a pair of spaced arms, each of said arms pivotally mounted to one side of said head adjacent its upper end and depending from said head; resilient means urging said arms apart; a track, said track including a primary portion adjacent said arms and parallel to the centerline of said clasp member; a secondary portion spaced from said primary portion in a direction remote from the centerline of said clasp member; the lower end of said secondary portion depending below said primary portion and the upper end of said secondary portion converging with said primary portion; a switch element in said primary track pivotally mounted at its lower end; the upper end of said switch portion contacting said primary portion at the point of conversion of said primary portion and said secondary portion; means urging said switch element into alignment with said primary portion; means for vertically, reciprocably moving said clasp member; a guide on each of said arms for contacting said track whereby as said clasp element is moved downwardly said guide will urge said arms together until said guide passes around the end of said primary portion and contacts said secondary portion for allowing said arms to separate until said guide transverses the end of said secondary portion converging with said primary portion.

2. In a hoist as set forth in claim 1 wherein a flange is mounted on the lower end of each of said arms; each of said flanges directed toward the other for engaging a flask therebetween when said guide contacts said primary portion of said track.

3. In a hoist for a foundry flask, the combination comprising: a frame; a clasp member including a vertically reciprocable head and a pair

of spaced arms, each of said arms pivotally mounted to one side of said head adjacent its upper end and depending from said head; resilient means for urging said arms apart; a track adjacent each of said arms and having a vertical straight portion parallel to the centerline of said clasp member and a loop portion at the lower end of said straight portions, said loop portion converging with said straight portion intermediate the ends of said straight portion; each of said loops disposed away from said centerline of said clasp member; a self-returning switch in each of said straight portions at the conversion of said loop portions and said straight portions; means for vertically, reciprocably moving said clasp member; a guide on each of said arms contacting said track whereby said arms will be urged together when said guide traverses said straight portion of said track and separated when said guide traverses the lower end of said loop portion of said track.

4. In a hoist as described in claim 3 wherein said arm includes a pair of spaced members; an L-shaped angle mounted to the lower ends of each pair of spaced members; each of said angles having a leg extending toward the centerline of said clasp member for supporting a flask when said guides are traversing said straight portion of said track.

5. In a hoist for a foundry flask, the combination comprising: a frame; a clasp member including a vertically reciprocable head and a pair of spaced arms, each of said arms pivotally mounted to one side of said head adjacent its upper end and depending from said head; resilient means for urging said arms apart; a guide on each of said arms extending away from the centerline of said clasp member; a first vertical track mounted on said frame adjacent each of said arms and contacting said guide for urging said arms together as said clasp member travels in one vertical direction; a second track converging with said first track and spaced from said first track in a direction away from said centerline of said clasp member for permitting said arms to separate a predetermined distance and urging said arms together as said clasp member travels in the opposite vertical direction.

STANLEY JAMES GEDRIS.
